HARVESTING MACHINERY.

1,233,399.

Specification of Letters Patent. Patented July 17, 1917.

Application filed February 6, 1913. Serial No. 746,548.

To all whom it may concern:

Be it known that we, CLEMMA R. RANEY, BERT R. BENJAMIN, and ROBERT C. LIVESAY, citizens of the United States, residing at 5 Chicago, Oak Park, and Moline, respectively, in the county of Cook, county of Cook, and county of Rock Island, respectively, and State of Illinois, have invented certain new and useful Improvements 10 in Harvesting Machinery, of which the following is a full, clear, and exact specification.

Our invention relates to harvesting machinery.

15 It has for its object to control the sheaf binding and discharging mechanism of a binder in an improved manner and render the same especially adapted to use in connection with a shocker. A further object of 20 our invention is to place the sheaf discharging mechanism of a binder under the control of the shocker so that the latter sets this mechanism in operation to deliver the sheaves only at predetermined times best 25 suited to the satisfactory operation of the shocker. We attain these objects by the provision of improved controlling means automatically coöperating with the sheaf delivering mechanism of a shocker and the 30 sheaf forming and discharging mechanism of a binder in an improved manner to lock or unlock the binder automatically at predetermined times in the operation of the shocker, and thereby automatically control 35 the discharge of the sheaves from the binder and the delivery of the same to the shocker.

In order to disclose our invention clearly and fully, we have illustrated one embodiment of the same in the accompanying 40 drawings, wherein the same is shown to be adapted to use in connection with an automatic shocker of the Raney type and a binder of the McCormick type. It is to be understood, however, that our invention is 45 susceptible of assuming other forms than that shown herein for purposes of illustration.

Figure 1 is a front elevation of the binder and coöperating mechanism.

Fig. 2 is an elevation of a shocker and the 50 stubbleward side of the binder.

The construction shown, when broadly considered, comprises an automatic shocker coöperating in an improved manner with the sheaf forming and discharging mechanism of an automatic binder through improved automatic operating and controlling mechanism hereinafter more specifically described.

The shocker shown is provided with an 60 automatic sheaf delivering member or fork 1, adapted to be oscillated about its pivot 2 on a shocker frame 3 through a resilient crank connection 4 and a chain and sprocket connection 5, driven from a suitable source 65 of power in such a manner as to deliver sheaves ejected from a binder to the cradle 3' and the shock binding and discharging mechanism of the shocker operable upon the same when therein. The sheaves are received by the fork 1 when in the dotted line 70 position shown in Fig. 2, and are delivered thereby to the cradle 3' and the binding and discharging mechanism carried at the rear of the shocker frame 3, when the fork is in 75 the full line position shown. Inasmuch as the shock binding and discharging mechanisms of the shocker, however, form no part of our joint invention, a specific description and illustration of the same has been 80 omitted from this case in order to facilitate consideration of the same.

The sheaf delivering mechanism of the shocker is automatically controlled in any desired manner, as, for instance, by a longitudinally extending tripping member 6 pivotally mounted on the front of the frame 3 and having upon its front end an upwardly extending tripping arm 7 projecting upward at one side of the member 1 90 when in sheaf receiving position and in the path of the sheaves delivered thereto. This tripping member 6 is provided with a bowed clutch controlling member 8 upon its rear end engaging in a predetermined position 95 with the clutch controlling finger 9 of a clutch 10 controlling the connection of the sheaf delivering mechanism to its source of

power. Means are likewise provided in the shape of a lever 11, pivotally and resiliently mounted at 12 upon a portion of the frame 3 adjacent the fork pivot 2 and operable through one of the link connections 13 of the shock binding mechanism, to engage the clutch controlling finger 9 and throw the sheaf delivering mechanism out of gear while the binding mechanism is being operated. As shown, the sheaf delivering member or fork 1 of the shocker is supported in its sheaf receiving position upon a bar or pipe 14 projecting from beneath the binder deck 15 of a binder.

In our improvement we provide improved automatic mechanism actuated automatically by the sheaf delivering member 1 as it moves to and from this sheaf receiving position to lock or unlock the sheaf discharging mechanism of the binder and thus automatically control and time the delivery of sheaves from the binder to the shocker. These means are shown to include a pivoted tripping lever 16 normally disposed in the full line position shown in Fig. 1, wherein it extends into the path of the movable sheaf delivering member 1. This lever 16 is pivotally connected through a link connection 17, to a member 18 controlling the connection of the sheaf discharging mechanism of the binder to its power shaft. As shown herein, the tripping lever 16 is a substantially L-shaped and mounted at the upper end of a standard 19 projecting upwardly from the pipe 14 at a point between the fork 1 and the binder deck 15, and substantially beneath the outer edge of an elongated supplemental binder deck 20 supported by the pipe 14. The long arm of this lever 16 extends beneath the fork 1, while the short downwardly extending arm of the same is pivotally connected to the link 17. This link 17 is limited in its movement by an upwardly extending guide 21 carried by the pipe 14, and is pivotally connected at its inner end at a point substantially beneath the outer edge of the deck 15, to a downwardly extending substantially U-shaped portion 22 of the binder clutch controlling member 18, journaled at 23 beneath the outer edge of the binder deck 15. One end of this clutch controlling member 18 is provided with an inwardly extending arm 24 extending substantially at right angles to the body portion thereof and provided at its end with a downwardly curved or bowed portion 25, having a laterally extending lug 26 formed on the end thereof and protruded into the same vertical plane as the clutch controlling pawl 27 of the binder clutch 28, and movable into or out of engagement therewith when the tripping lever 16 is rocked about its pivot by the movement of the fork 1.

The binder and the sheaf forming and discharging mechanism *per se*, while improved in certain respects to permit them to coöperate with our improved controlling mechanism, are of standard construction and have accordingly not been illustrated in detail, since the general construction of the same is well-known. The parts thereof are shown in front elevation in Fig. 1. This mechanism includes a rotating power shaft 29 operatively connected through any suitable mechanism (not shown) with the main wheel 30 of the binder, and carrying upon its outer end the binder clutch 28. This power shaft 29 is operatively connected to discharge arms 31 through a substantially one to three gearing connection 32—33 (Fig. 2) and is adapted to rotate the same at predetermined times to throw the discharge arms 31 about their axis upon a shaft 34 and discharge a sheaf onto the supplemental deck 20 and beneath the spring bars 35 thereof. Operatively connected to the shaft 34 is a cam wheel 36 adapted to actuate a link and crank connection 37—38 pivotally connected at its lower end to a clutch controlling member 39 which is splined intermediate its ends upon a rotatable shaft 40, carried beneath the binder deck, and is movable into and out of engagement with the clutch controlling pawl 27 of the binder clutch. In order that the link connection 37—38 may also control the clutch controlling member 18, it is provided with a pivot pin 41 which protrudes into the plane of the arm 24 of the member 18 in such a manner as to underlie the same when raised beneath the same. A compressor arm or trip hook 42 is mounted on an arm 43 fixed to the shaft 40 beneath the binder deck and protrudes upward through the same in the path of the grain. This compressor arm is resiliently mounted in the usual manner and acts as an abutment against which the grain is packed by the usual packer arms 44 pivoted to a shaft 45 and operated through the usual crank connection from the shaft 29. Inasmuch as the resilient connection of the compressor arm 42 is well-known, illustration of the same has been omitted. At a point beneath the binder deck the compressor arm 42 is rigidly attached to the shaft 40 so that upon movement of the same to and from the dotted position shown it also acts to rotate this shaft. Coöperating with this mechanism when a sheaf has been packed is the binding needle 46, which is rotatably mounted upon a shaft 47 and operatively connected to the cam wheel 36 through a pivoted link connection 48—49, so that when the cam 36 is rotated the needle 46 is thrown around into a position wherein its twine carrying end extends through the breast-plate 50 of a suitable knotter 51, and co-

operates with the knot tying mechanism thereof to bind the sheaf. It is to be understood that all of the mechanism above described is carried either on the binder frame 52 or on a supplemental frame 53 and 54 between the binder frame and the pipe 14.

The operation of the mechanism shown herein is as follows: Let us assume that the parts are in the position shown in full lines in Fig. 1, wherein one sheaf is upon the supplemental deck and another is bound but not yet discharged thereon, the lug 26 of the clutch controlling member 18 is in engagement with the pawl 27 of the clutch 28, the discharge arm 31 is in the lower dotted line position shown, the needle 46 and link connection 48-49 are raised, the clutch controlling member 39 is in the raised position shown, the compressor arm 42 is forced backward about its axis on the shaft 40, the pivoted tripping member 16 is in the raised full line position shown, and the sheaf delivering member 1 is just coming into contact with the latter. As the member 1 drops upon the tripping lever 16, the latter is thrown about its pivot to the dotted line position shown, and through the link 17 throws the clutch controlling member 18 upward, causing its lug 26 to be disengaged from the clutch pawl 27. The clutch 28 is thus free to connect the power shaft 29 with the discharge arm 31 and the rotating cam wheel 36. The discharge arm 31 is thrown from the lower dotted position shown toward the upper dotted position, sweeping outward the sheaf which has just been bound and forcing the same up against the sheaf resting upon the supplemental deck 20 in such a manner as to force the latter sheaf over the edge of the deck upon the sheaf delivering member 1. As this last mentioned sheaf falls upon the tines of the member 1, it strikes against the tripping lever 7 controlling the operation thereof and, through the sheaf delivering mechanism, throws the arm 1 backward about its pivot to deliver the sheaf to the shocker cradle. As the member 1 is raised from engagement with the tripping lever 16 and the discharge arm 31 is rotated about its pivot, the cam wheel 36 operates the link connection 37-38, raising the same, and the compressor arm 42, so that the latter is again in the path of the grain. At the same time, since the clutch controlling member 39 is movable with the link connection 37-38, the latter is thrown into engagement with the binder clutch pawl 27 to prevent the fourth revolution of the shaft 29 and place the parts in position to be again operated when the next sheaf is bound. As soon as the member 42 is returned to its normal position the continuously operating packer arms 44 pack another sheaf against the same, and when the

pressure of the grain against the arm 42 has reached a predetermined degree, the latter is forced downward again to raise the clutch controlling member 39 and again release the clutch pawl 27. The shaft 29 is thus again freed so that it can move through two revolutions to rotate the discharge arm 31 from the upper dotted position to the lower dotted position. During this rotative movement the binding mechanism is operated, the link connection 48-49 rotating from the dotted line position to the full line position and advancing the binding needle 46 to coöperate with the knitter 51 and bind the sheaf. At the time, however, that the sheaf discharging arm 31 has moved around to the lower dotted position shown, the link connection 37-38 has also been depressed by the cam wheel 36 to throw the clutch controlling member 39 upward and release the clutch controlling member 18 so that the latter falls downward of its own weight into the path of the clutch controlling pawl 27 in position to engage the latter when it completes its second revolution. It is to be noted that in this position the parts are again returned to their initial position described above, the sheaf forming, binding and discharging mechanism being stopped and the tripping lever 16 being raised ready to be again engaged by the sheaf delivering member 1. Obviously, this operation will continue automatically during the oscillation of the sheaf delivering member 1. It is further obvious that this operation will be automatically discontinued during the shock binding operation by the movement of the binder link 13, which acts to throw the member 11 into engagement with the clutch pawl 9 and thus render the sheaf delivering member 1 inoperative.

It is to be noted that in the construction shown the shocker, through the position of its fork, controls the delivery of sheaves thereto and determines whether or not the sheaf discharging mechanism of the binder is operated, and that, while the sheaf forming mechanism of the binder is free to operate, the discharging mechanism thereof is held inoperative until the fork assumes a predetermined position wherein it is ready to receive the sheaf therefrom. It is further to be noted that at all times the controlling mechanism described herein not only acts automatically to interrupt the discharge of a sheaf or sheaves from the binder when the fork is delayed in returning to sheaf receiving position, but also acts to delay the discharge of the sheaves from the binder when the latter is operating in heavy grain and the natural tendency of its binding and discharging mechanism is to increase the number of bundles discharged in a given time beyond the capacity of the fork. In

other words, when the binder is operating in heavy grain where the tendency of its discharging mechanism is to increase the number of discharging operations in a given time beyond the number of operations of the fork in that same time, through the controlling mechanism therefor herein described, means are provided for automatically maintaining the number of operations of the discharging mechanism of the binder in a given time, the same as the number of operations of the fork in that time and coincident in each case with the return of the fork to sheaf receiving position. Obviously also when operating under service conditions where the grain runs light or heavy in patches around the field, by providing the sheaf delivery mechanism with capacity greater than the amount of grain usually coming up the conveyers, this delivery mechanism will operate to relieve any congestion in the binder caused by the retardation of the discharging mechanism thereof during heavy grain conditions, or while the shock is being discharged, very shortly after the binder passes out of the heavy grain or the fork has commenced building the next shock. In fact, it has been found that, when operating under the average conditions in patched or spotted fields only two or three operations of the fork are required after the binder has passed out of the heavy grain or the shock has been set to permit the fork to catch up and reduce the congestion. When operating on large areas of heavy grain, however, it is of course to be understood in this connection that the binding mechanism may, if desired, be so adjusted as to increase the size of the bundles bound thereby and thus increase the capacity of the binder and shocker in such a manner as to avoid continued congestion.

While we have described one form of our invention in this application, it is to be understood that the form shown herein is susceptible of modification, and that our invention is not limited to the specific embodiment of the same chosen for purposes of illustration.

50 What we claim as our invention, and desire to secure by Letters Patent, is:

1. In combination, sheaf discharging mechanism, shocker mechanism, and means controlled by the latter controlling the delivery of each sheaf from said discharging mechanism.

2. In combination, sheaf discharging mechanism, shocker mechanism, and means controlled thereby for regulating the intervals between the sheaves delivered by said discharging mechanism.

3. In combination, sheaf discharging mechanism, shocker mechanism, and means controlled by the latter controlling the de-

livery time of each sheaf from said discharging mechanism. 65

4. In combination, automatic sheaf discharging mechanism, means for receiving the discharged sheaves, and means coöperating therewith for preventing the intervals between the operations of said discharging mechanism from falling below a certain minimum under all grain conditions. 70

5. In combination, automatic sheaf discharging mechanism, and intermittently operating controlling means for preventing the intervals between the operations thereof from falling below a certain minimum upon an increase in the quantity of grain to be acted upon thereby. 75

6. In a harvesting machine, sheaf discharging mechanism, and mechanism actuated by said discharging mechanism automatically controlling each operation thereof. 80

7. In a harvesting machine, sheaf discharging mechanism, means for receiving the discharged sheaves and mechanism regulating the delivery time thereof set in operation by said sheaf receiving mechanism. 85

8. In a harvesting machine, sheaf discharging mechanism, and mechanism actuated by a sheaf discharged therefrom automatically timing successive operations thereof. 90

9. In a harvesting machine, a binder including sheaf discharging mechanism, and means automatically locking said mechanism at a point intermediate the ends of its cycle of operation. 95

10. In a harvesting machine, sheaf discharging mechanism, and sheaf delivery mechanism for controlling said discharging mechanism during the interval between successive operations of said discharging mechanism. 100

11. In a harvesting machine, sheaf discharging mechanism, sheaf delivery mechanism including a movable sheaf delivery member receiving sheaves therefrom, and means engageable at intervals by said delivery member controlling said discharging mechanism. 105

12. In a harvesting machine, sheaf discharging mechanism, sheaf delivery mechanism including a movable sheaf delivery member receiving sheaves therefrom, and tripping mechanism engageable at intervals by said delivery member controlling said discharging mechanism. 115

13. In a harvesting machine, a binder including sheaf discharging mechanism, and means interrupting the movement of said discharging mechanism prior to the completion of the discharging operation. 120

14. In a harvesting machine, coöperating sheaf binding and discharging mechanism, and means coöperating therewith stopping the discharging mechanism after a sheaf 125

has been bound and prior to the discharge thereof.

15. In a harvesting machine, a binder including sheaf discharging mechanism, and means interrupting the operation of the same at a fractional part of its cycle of operation.

16. In combination, a sheaf discharging arm rotatable through 360° and effecting during each cycle of its operation the discharge of a sheaf, operating mechanism therefor, and means for positively stopping the movement thereof when said arm is approaching its sheaf discharging position and is in proximity to a bundle and in the path of the grain and subsequently continuing said movement in the same direction.

17. In a harvesting machine, sheaf discharging mechanism, controlling mechanism therefor, a shock receptacle and co-operating sheaf delivery mechanism delivering sheaves thereto controlling said controlling mechanism.

18. In a harvesting machine, sheaf discharging mechanism, controlling mechanism therefor, and co-operating sheaf delivery mechanism controlled by a sheaf discharged by said discharging mechanism and controlling the latter.

19. In a harvesting machine, sheaf discharging mechanism, controlling mechanism therefor, a shock receptacle and co-operating sheaf delivery mechanism delivering sheaves thereto timing each operation of said controlling mechanism.

20. In combination, a binder, sheaf discharging mechanism thereon, sheaf delivery mechanism including a co-operating swinging sheaf delivery member, and means controlled by said member for regulating the interval between the sheaves discharged thereby.

21. In combination, a binder, sheaf discharging mechanism thereon, a shock receptacle, means including a co-operating swinging sheaf delivery member, delivering sheaves thereto, and means set in operation by said delivery member controlling said discharging mechanism.

22. In combination, a binder, sheaf discharging mechanism thereon, a shock receptacle, means including a co-operating swinging sheaf delivery member delivering sheaves thereto, and means actuated by said delivery member timing the operation of said discharging mechanism.

23. In combination, sheaf discharging mechanism, a co-operating sheaf delivery member, and means controlled by said member for interrupting the movement of said discharging mechanism at a point intermediate the ends of its cycle of operation.

24. In combination, sheaf discharging mechanism, controlling mechanism for said

mechanism normally holding the same out of operation, a shock receptacle and sheaf delivery mechanism delivering sheaves thereto controlling said controlling mechanism.

25. In a harvesting machine, a binder including sheaf discharging mechanism, controlling mechanism therefor, and supplemental controlling mechanism co-operating therewith interrupting the operation of said discharging mechanism prior to the completion of the discharging operation.

26. In a harvesting machine, automatic sheaf discharging mechanism, a shock receptacle, automatic sheaf delivery mechanism delivering sheaves thereto, and means whereby said sheaf discharging mechanisms may be thrown out of operation during a predetermined interval in each cycle of its operation controlled by said sheaf delivery mechanism.

27. In a shocking machine, sheaf discharging mechanism, a shock receptacle mechanism including a co-operating movable sheaf delivery member delivering sheaves thereto, mechanism operable upon the delivery of a sheaf to said delivery member to set the latter in operation, and means preventing the delivery of sheaves therefor until the same has returned to its initial position.

28. In a shocking machine, a shock receptacle, movable sheaf delivering means delivering sheaves thereto, mechanism operable upon the delivery of a sheaf to said delivery means to set the latter in operation, and means controlled by said sheaf delivering means preventing the delivery of sheaves thereto until said delivering means has returned to its initial position.

29. In combination, sheaf discharging mechanism, a shock receptacle, mechanism including a movable sheaf delivery member delivering sheaves thereto, mechanism automatically operated by the delivery of a sheaf to said delivery member to set the latter in operation, and automatic means for preventing the delivery of sheaves to said delivery member during a part of its cycle of operation.

30. In combination, sheaf discharging mechanism, a shock receptacle, mechanism including a movable sheaf delivery member delivering sheaves thereto, mechanism automatically operated by the delivery of a sheaf to said member to set the latter in operation, and automatic means controlled by said delivery member for preventing the delivery of sheaves thereto during a predetermined part of each cycle of operation thereof.

31. In a shocking machine, sheaf delivering mechanism operable upon the delivery of a sheaf thereto, a sheaf receiving member

- coöperating with said mechanism, and means preventing the delivery of sheaves to said sheaf delivering mechanism while the latter is delivering a sheaf to said receiving member. 65
32. In combination, a grain binder, sheaf discharging mechanism thereon, a shock receptacle, mechanism including a swinging sheaf delivery member delivering sheaves thereto, and mechanism including a trip engageable by said delivery member controlling said sheaf discharging mechanism. 70
33. In combination, a binder, sheaf discharging mechanism thereon, a shock receptacle, means including a swinging sheaf delivery member delivering sheaves thereto, and means controlled by said sheaf delivery member controlling said discharging mechanism and setting the same in operation when said delivery member occupies a predetermined position with respect thereto. 75
34. In combination, a binder, sheaf discharging mechanism thereon, a shock receptacle, means including a movable sheaf delivery member delivering sheaves thereto normally disposed in position to receive a sheaf from said discharging mechanism, and means controlled by said member for interrupting the discharge of sheaves from said discharging mechanism at all times except when said member is in receiving position. 80
35. In combination, automatic sheaf discharging mechanism, automatic sheaf delivery mechanism coöperating therewith, means for interrupting the operation of said delivery mechanism, and means for maintaining the intervals between the operations of the discharging mechanism substantially the same before and after said interruption. 85
40. 36. In a shocking machine, sheaf discharging mechanism, a shock receptacle, means including a movable sheaf delivery member delivering sheaves thereto, controlling mechanism for said delivery member engaged and actuated by a sheaf delivered to said member, means actuated by said member for preventing the delivery of sheaves therein during the delivery of sheaves thereby. 90
50. 37. In a shocking machine, sheaf delivering mechanism operable upon the delivery of a sheaf thereto, a sheaf receiving member coöperating with said mechanism, and sheaf discharging mechanism controlled by said delivering mechanism interrupting the delivery of sheaves thereto while the latter is delivering a sheaf to said receiving member and in turn controlling the actuation of said sheaf delivery mechanism upon its return to its initial position. 95
60. 38. In a shocking machine, a movable sheaf delivering member, means for operating said delivering member actuated upon the delivery of a sheaf thereto, a sheaf receiving member coöperating with said mechanism, and means preventing the delivery of sheaves to said sheaf delivering mechanism while the latter is delivering a sheaf to said receiving member, means movable during the binding of the sheaves in said sheaf receiving member, and means controlled by said last mentioned means for rendering said sheaf delivering member inoperative during the binding operation. 100
39. In combination, a binder, sheaf forming and discharging mechanism carried thereon, a shocker coöperating therewith, and means controlled by said shocker for automatically interrupting said discharging mechanism after the completion of the operation of said binding mechanism. 105
40. In combination, automatic sheaf binding and discharging mechanisms, sheaf delivery mechanism controlled by said discharging mechanism, and mechanism controlled by said delivery mechanism and in turn controlling said discharging mechanism interrupting at intervals the operation of said discharging mechanism after the completion of the binding operation. 110
41. In combination, a binder, automatic sheaf discharging mechanism carried thereon, an automatic shocker, a movable sheaf delivering member carried thereon, and tripping mechanism automatically actuated by said sheaf delivering member automatically controlling the operation of said sheaf discharging mechanism. 115
42. In combination, a binder deck, sheaf discharging mechanism thereon, a sheaf delivery member normally disposed beneath said binder deck and movable out of normal position, means for holding said discharging mechanism out of operation, and means whereby said discharging mechanism is thrown into operation whenever said delivery member returns to normal position. 120
43. In combination, a sheaf discharging arm, a sheaf binding needle, knot tying mechanism coöperating with the latter, sheaf forming mechanism, mechanism for operating said elements, means set in operation by said sheaf forming mechanism controlling the operation of said discharging arm, and means operatively connected to said discharge arm for rendering the same temporarily inoperative after the sheaf is bound by said binding mechanism and prior to the discharge thereof. 125
44. In combination, sheaf forming, binding and discharging mechanism, operating mechanism therefor, including a binder clutch, a clutch controlling member, and a supplemental clutch controlling member, said clutch controlling members being operatively connected to a moving part of 130

said mechanism and at intervals successively engaging said clutch to control said first mentioned mechanisms.

45. In combination, sheaf binding and discharging mechanism, operating mechanism therefor including a movable clutch member normally movable through a predetermined path, and means for controlling said discharging mechanism including a 10 clutch controlling member projectable into engagement with said clutch member at a point intermediate the ends of its normal path of movement.

46. In combination, a pivoted compressor 15 arm, sheaf packing mechanism coöperating therewith, operating mechanism therefor, a binder clutch included in said operating mechanism, means controlled by said compressor arm controlling the connection of 20 said clutch, and an auxiliary clutch controlling member operatively connected to said operating mechanism and movable into engagement with said clutch between each movement of said controlling means into 25 engagement therewith.

47. In combination, a binder, a binder deck thereon, sheaf binding and discharging mechanism on said binder deck, an upwardly and rearwardly swinging sheaf delivery member, operating mechanism for 30 said member, a trip disposed in the path of said member, a binder clutch, operative connections between the same and said binding and discharging mechanism, and clutch controlling connections between said trip and 35 said binder clutch controlled by a moving part of said binding and discharging mechanism.

48. In combination, a frame, sheaf binding mechanism thereon, sheaf discharging mechanism thereon, a binder deck, a binder clutch, clutch controlling mechanism operatively connected to said binding and discharging mechanism, a coöperating clutch 45 controlling member operatively connected to one of said mechanisms, an operating connection operatively connected to said controlling member, and a trip member operatively connected to said operating connection 50 and disposed beneath said binder deck at a point adjacent the delivery end thereof.

49. In combination, sheaf forming and binding mechanism, sheaf discharging mechanism, operating mechanism for said several 55 mechanisms, a binder clutch included in said operating mechanism, a clutch controlling member operatively connected to said sheaf forming mechanism, and a supplemental clutch controlling member operatively connected to said discharging mechanism.

50. In combination, sheaf forming and binding mechanism, sheaf discharging mechanism, operating mechanism for said sev-

eral mechanisms, a binder clutch included in 65 said operating mechanism, a clutch controlling member operatively connected to said sheaf forming mechanism, and a supplemental clutch controlling member operatively connected to said sheaf discharging mechanism and engageable with said clutch 70 during the interval when the latter is released by said first mentioned controlling member.

51. In combination, sheaf discharging mechanism, a sheaf binding needle, a compressor arm, operating mechanism for said elements, a binder clutch included therein and controlled by said compressor arm, means operatively connecting said sheaf discharging mechanism and said compressor 80 arm, means operatively connecting said sheaf discharging mechanism and said needle, and supplemental clutch controlling mechanism controlled by said sheaf discharging mechanism and coöperating with 85 said compressor arm to interrupt the movement of said sheaf discharging mechanism and said sheaf binding mechanism.

52. In combination, sheaf discharging mechanism, sheaf binding mechanism, a 90 compressor arm, operating mechanism for said mechanisms, a binder clutch included therein controlled by said compressor arm, means operatively connecting said sheaf discharging mechanism and said compressor 95 arm, means operatively connecting said sheaf discharging mechanism and said needle, supplemental clutch controlling mechanism controlled by said sheaf discharging mechanism and coöperating with 100 said compressor arm to control the movement of said sheaf discharging mechanism and a tripping member operatively connected to said supplemental clutch controlling mechanism and through the latter controlling the operation of all of said previously mentioned elements.

53. In combination, sheaf forming, binding and discharging mechanism, mechanism for operating the same, a clutch included in 110 said operating mechanism and controlling the connection of said mechanisms thereto, a clutch controlling member operatively connected to said sheaf forming mechanism and actuated thereby to release the clutch and 115 operatively connect said operating mechanism to said binding mechanism upon the completion of the sheaf forming operation, a supplemental clutch controlling member normally engageable with said clutch operatively connected to said discharging mechanism and held out of engagement with 120 said clutch thereby during the interval that said first mentioned controlling member is in engagement therewith and releasing 125 mechanism for said last mentioned clutch

controlling member operatively connected thereto.

54. In combination, sheaf forming, binding and discharging mechanisms, mechanism for operating the same, a clutch included in said operating mechanism and controlling the connection of said mechanisms thereto, a clutch controlling member operatively connected to said sheaf forming mechanism and operated thereby upon the completion of the formation of a sheaf to release said clutch and throw said binding mechanism into operation, a supplemental clutch controlling member operatively connected to said discharging mechanism and engageable with said clutch to throw said mechanism out of operation prior to the comple-

tion of its cycle of operation, and clutch tripping mechanism operatively connected to said last mentioned clutch controlling member operable to release said clutch and free said discharging mechanism to complete its cycle of operation. 20

In testimony whereof we affix our signatures, in the presence of two witnesses.
